CLAIM

The ornamental design for an end panel for a portable wireless telephone, as shown and described.

DESCRIPTION

FIG. 1 is a perspective view of the front and one side of an end panel for a portable wireless telephone showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The portions of the portable wireless telephone shown in broken lines are not part of the claimed design.
